[57] CLAIM

The ornamental design for a chair, as shown and described.

DESCRIPTION

FIG. 1 is a front perspective view of a chair showing my new design;

FIG. 2 is a right side elevational view;

FIG. 3 is a top plan view;

FIG. 4 is a front elevational view;

FIG. 5 is a rear elevational view; and

FIG. 6 is a bottom plan view thereof.

The undisclosed left side is a mirror image of the right side shown in FIG. 2.

FIGS. 2 through 6 have been drawn to an enlarged scale with respect to FIG. 1.
